ABRASIVE WHEEL AND MOUNT THEREFOR

Herbert S. Indge, Westboro, Mass., assignor to
Norton Company, Worcester, Mass., a corpora-
tion of Massachusetts

Application June 25, 1935, Serial No. 28,236

2 Claims. (Cl. 51—103)

This invention relates to abradant wheels and apparatus for mounting them.

One object of the invention is to provide an abradant wheel of relatively large peripheral 5 surface area. Another object of the invention is to provide a conical abradant wheel of relatively great length with relation to its average diameter. Another object of the invention is to provide a wheel mounting and wheel construction 10 of frusto-conical form which shall reduce wheel wastage. Another object of the invention is to provide a wheel construction of interchangeable sections. Other objects will be in part obvious or in part pointed out hereinafter.

15 The invention accordingly consists in the features of construction, combinations of elements and arrangements of parts, as will be exemplified in the structure to be hereinafter described, and the scope of the application of which will be indicated in the following claims.

In the accompanying drawings, in which is disclosed one of many possible embodiments of the mechanical features of the invention,

Figure 1 is a view of a portion of a continuous 25 lapping machine illustrating a pair of abradant wheels and mounting apparatus therefor applied thereto, one wheel being shown in axial section and the other in front elevation;

Figure 2 is a vertical sectional view taken on 30 the line 2—2 of Figure 1;

Figure 3 is a vertical sectional view taken on the line 3—3 of Figure 1.

This invention is in part disclosed in my co-pending application Serial No. 5,271, filed Febru- 35 ary 6, 1935, now Patent No. 2,087,874, dated July 20, 1937, relating to lapping machines. In that application I have disclosed a lapping machine having a pair of frusto-conical lapping wheels adapted to finish a cylindrical work-piece which 40 is maintained between the wheels by guides, the work-piece being fed through the machine by skewing one or both of the wheels. The afore- 45 said copending application further discloses an apparatus for shaping the originally frusto-conical wheels so that, despite the fact that they are skewed, they will effectively lap a true cylindrical work-piece. Such shaping modifies the peripheral surface of each wheel by producing therein a slight concavity. The dressing apparatus dis- 50 closed in the copending application will not be described in detail herein particularly insomuch as, so far as the present invention is concerned, any substitute might be employed; nevertheless, for a clearer understanding of the shapes of the 55 wheels according to the present invention, it is

noted that the dressing device is mounted for traverse between the wheels in a rectilinear path, and, insomuch, as herein described, the wheels are mounted for angular adjustment on an axis at right angles to their axis of rotation, dressing 5 or truing of the wheels with such dressing device may produce a concave contour therein if they are skewed with respect to such rectilinear path. Insomuch as I rely for the production of certain effects in lapping upon moving abrasive material 10 at an angle to the axis of the work-piece, which is not a right angle, I skew the axes of the wheel spindles with respect to the said rectilinear path and dress the wheels to produce such concave surface which generates a true cylindrical surface or 15 leaves a true cylindrical surface on the work-piece. So far as certain claims are concerned, therefore, each wheel and each wheel section herein described may be considered to have a slight concavity in its peripheral surface; insomuch as ordinarily such concavity is of a slight degree, it has not been illustrated in the drawings, and insomuch as, further, the degree of concavity is a variable depending upon setting of the 20 wheels and the particular type or work-piece being lapped. The present application is directed to the construction and mounting of the wheels per se.

In the manufacture of abrasive wheels there are and have been certain practical limits on the 30 size thereof both in an absolute sense and relatively with respect to the ratio of thickness to diameter. Whatever might be regarded as the limit in either of these respects, it is not that a 35 larger wheel or a thicker wheel could not be made, but that it is not convenient and economical to do so. In the case of large wheels and wheels which are extremely thick with respect to their diameters, a disproportionate number 40 might have to be rejected because of the development of cracks in the firing or baking or other heat treatment or otherwise; such wheels, however made, are difficult to handle while in process of manufacture, a so-called "green wheel" (an unfired or unbaked wheel form) being an extremely delicate thing. Accordingly the formation 45 of a wheel of the shape disclosed in the present and in the copending application referred to, represented a problem. By the construction and features hereinafter described I 50 not only solved the above mentioned problem, but have also considerably reduced wheel wastage.

Referring now to Figure 1, there is provided in the lapping machine above referred to a base 10 rigidly secured to which is a supporting plate 11. 55

This plate 11 has a milled or planed horizontal upper surface 12 upon which rests a table 13. A trunnion 14 having a vertical axis extends downwardly from the under side of the table 13 and 5 fits in a bore 15 in the supporting plate 11, and thus the table 13 is restrained against any horizontal movement on the plate 11 except an angular movement. The weight of the machine parts and the broad surface 12 of the plate 11 and the 10 cooperating under surface of the table 13 secures the table 13 against any vertical movement or strain. Thus the table 13 has a firm foundation and may be moved angularly about the vertical axis of the trunnion 14, but not otherwise.

15 The table 13 supports an abrasive wheel and spindle to be described, and a similar wheel is mounted above it. Considering now the support for the upper wheel, the machine of the copending application referred to has a column attached 20 to the base 10, which column is not shown herein as, so far as the features of this invention are concerned, it may be of any desired form, and mounted on the column is a slide adjustable in a vertical direction on the column, the slide being likewise not shown herein, and extending forwardly from the slide is an overhanging support 20 which may be integral with the slide; thus in a sense the casting 20 shown in the drawings is part of said slide. On the under side of the overhanging support or over-arm 20 is a large flat plane surface 21 extending approximately over the horizontal upper surface 12 of the supporting plate 11. Held against this surface 21 is a table 22, and a trunnion 23 fitting in a bore 24 mounts 25 the table 22 for angular adjustment. The table 22 is prevented from falling and is held against the surface 21 by means of cooperating segmental guiding surfaces 25 and 26. The trunnion 23 may be provided with radial supporting plates 27 to 30 assist in supporting the load. The upper and lower abrading wheels 30 and 30a respectively are, at least initially in this embodiment of the invention, frusto cones, and they and the journaling means for them and their mounting upon their spindles being similar, I have shown only 35 the upper wheel 30 in cross-section and it should be understood that the journaling means and spindle supports for the lower wheel 30a is similar to that for the upper wheel 30. It will also be noted from inspection of the drawings that the frusto-conical wheels 30 and 30a are oppositely disposed and the locus of the abrading throat is between the wheels, the work guides not being 40 shown herein.

35 Still referring to Figure 1, extending downwardly from the table 22 and desirably integral with it is a head 31. Likewise a head 31a extends upwardly from the table 13. Each head is hollow as shown in the case of the head 31, and formed on the inside thereof is a roller bearing race recess 32. The outer race 33 of a roller bearing seats in the recess 32 while the inner race 34 seats on a cylindrical portion 35 provided on a spindle 36. Conical rollers 37 are 45 shown located between the races 33 and 34.

40 The inner race 34 is held on the spindle 36 by means of a shoulder 38 on the spindle at one side of the race 34, and a sleeve 39 on the other side thereof. The thrust on the sleeve 39 is taken by an inner race 40 of a second roller bearing 45 which is mounted on a cylindrical portion 41 of the spindle 36 and which also abuts a square shoulder 42 on the spindle. Conical rollers 43 are located between the inner race 40 and an outer race 44 which is seated in a recess 45 pro-

vided in an annular member 46 which is secured in the head 31 fitting in a cylindrical bore 47 thereof. The annular member 46 has a circular recess 48 for the reception of a cap 49 which keeps grit out of the bearings and oil or grease 5 therein if desired. In order to take the thrust on the inner race 40 and to position both races 40 and 34 upon the spindle 36, the spindle 36 is threaded at 50 and a couple of nuts 51 and 52 are placed on the portion 50, the inner nut 52 being in contact with the race 40. Thus when the nuts are tightened thrust is exerted from the inner nut 52 to the race 40, from there to the sleeve 39 to the inner race 34 and against the shoulder 39. Insomuch as the outer races 33 and 44 are held between the recesses 32 and 45, the bearing means described constitutes an anti-friction radial and thrust bearing for the left-hand end of the spindle 36, there being a similar bearing in the head 31a for the similar spindle 36a. 10

15 The spindle 36 may be driven from inside the head 31. Keyed to the sleeve 39 is a worm wheel 55 which is driven by a worm 56 on a shaft 51 whose axis is at right angles to that of the spindle 36. The worm wheel 55 extends through a cutout 25 58 in a sleeve 59, and for the remaining features of the driving mechanism I will now refer to the similar construction in connection with the head 31a, as illustrated in the cross-sectional view of Figure 3. The spindle 36a has keyed thereto a 30 sleeve 39a to which is keyed a worm wheel 55a which is driven by a worm 56a keyed to a shaft 57a. There is a cutout 58a in a sleeve 59a which has a flange portion 60a that is bolted to the head 31a by bolts 61a, there being a shoulder 62a 35 which fits in a bore 63a in the head 31a. Thus the sleeve 59a is held in a fixed position in the head 31a, and the other end of the sleeve 59a fits in a bore 64a in the other side of the head 31a.

40 The worm 56a abuts a shoulder 65a on the shaft 57a, this shoulder receiving the driving thrust. The other end of the worm 56a abuts a sleeve 66a on the shaft 57a. The shaft 57a has a reduced portion 67a which is threaded at the end. A lock nut 68a holds an inner race 69a of 45 a ball bearing on the reduced portion 67a, but a slight clearance is provided, as shown. The thrust on the shaft 57a is taken by the bearings of a driving motor 70a but when the motor is slowing down, or when the thrust on the worm 56a is 50 reversed for any reason, the slight left-hand thrust of the worm 56a is taken by the sleeve 66a, transmitted to the inner race 69a, and taken by bearing balls 71a and thus transmitted to an outer race 72a and thence to a bearing cap 73a. 55 The outer race 72a is positioned in a recess 74a in the sleeve 59a and held therein by a shoulder 75a on the bearing cap 73a. The bearing cap may be held in position by bolts 76a. Thus the ball bearing consisting of races 69a, 72a and balls 60 71a is essentially a radial bearing.

65 The other end of the shaft 57a passes through a stuffing box 80a that is bolted by bolts 81a to the sleeve 59a, the stuffing box having a head 82a located in a recess 83a in the sleeve 59a and 65 having also packing 84a to keep oil or grease in the unit to lubricate all the parts referred to. The inner end of the stuffing box 80a abuts an outer race 85a of a ball bearing whose inner race 86a is mounted on the shaft 57a, there being 70 bearing balls 87a between these races. The race 85a is held in position also by a shoulder 88a in the sleeve 59a. The bearing just described constitutes another anti-friction radial bearing for the shaft 57a. The shaft 57a is driven by the 75

motor 70a through a coupling 90a. The motor 70a is mounted on a platform 91a which is integral with an extension 92a of the table 13. Thus the drive is not interfered with by adjustments 5 in angular position of the wheel 30a.

Considering again the upper spindle 36, the mechanism for driving it is similar to that already described, although a different means of allowing for adjustments in the angular position 10 of the wheel 30 may be provided, for example as shown in the copending application referred to. In order to seal oil or grease in the roller bearings described and to keep grit therefrom, packing 95 and a gland 96 may be provided. The gland 15 96 consists of nearly over-lapping annular portions on the outside of the head 31 and on a flange portion 97 of a hollow spindle or sleeve 99 which is connected to the driving and supporting spindle 36 by a spline connection 100.

20 Still considering the upper part of Figure 1, upon the hollow spindle 99 I mount a plurality of abrasive wheels 101, 102, 103, 104, 105, 106, 107 and 108. Each of these is a frusto-cone with an axial bore just fitting the outside of the hollow 25 spindle 99. The small end of the wheel 101 has a diameter just equal to that of the large end of the wheel 102, and all the others down to the end wheel 108 have diameters equal to that of the large ends of the adjacent wheels respectively. Preferably each wheel is of the same 30 thickness as all the others. While this invention contemplates the use of any kind of wheel so far as composition is concerned, I have achieved excellent results in a lapping machine 35 using fine grain silicon carbide in a shellac bond. Other grain may be used, as alumina, emery, corundum, garnet, quartz, and other bonds, as ceramic, rubber, synthetic resins, sodium silicate.

In the assembly of the entire wheel 30, the component 40 wheels 101 to 108 are slipped onto the spindle 99 in the order described and shown, and with the wheel 101 against the flange 97. Desirably the sides of each wheel excepting the large side of the wheel 101 and the small side of the 45 wheel 108 are coated with a suitable cement, such as, in the case of shellac bonded wheels, a coating of shellac. A washer 109 and a nut 110 fitting on a threaded portion 111 of the spindle 99 secure the individual wheels together as a unit 50 and compress the cement so that it will set. Before explaining the features of the wheel 30 further, I shall complete the description of the mounting means.

Still referring to the upper part of Figure 1, the 55 spindle 36 adjacent the right hand end of the outer hollow spindle 99 has a threaded portion 112 on which is located a nut 113 which clamps the spindle 99 against a shoulder 114 on the spindle 36 adjacent the flange 97. At the right-hand 60 end of the spindle 36 is a reduced cylindrical portion 115. Referring now to the upper right-hand part and also to the lower left-hand part of Figure 1, and also to Figure 2, the table 13 has attached to it ways 116a and the table 22 65 has attached to it ways 116. These are in the form of dove-tailed members, and small heads 117a and 117 respectively have complementary slideways 118a and 118 so that the heads 117 and 117a are 70 slidable, parallel to the axes of the wheels 30 and 30a on the tables 22 and 13 respectively. These heads 117 and 117a are provided with anti-friction bearings to journal the ends of the inner spindles, as shown in the case of the spindle 36 in Figure 1, the reduced

portion 115 of which is supported and journaled in the head 117.

Considering now the journals for the outer ends of the inner spindles, and referring to the upper right-hand part of Figure 1 and also to Figure 2, a cylindrical recess 120 is formed in the head 117, which recess is open at the right-hand end and has a shoulder 121 and an annular flange 122 at the left-hand end. An outer casting member 123 fits in the recess 120 against 10 the shoulder 121 and this member 123 has on either side thereof annular plates 124. An outer race 125 fits between these three last mentioned parts between which outer race 125 and an inner race 126 are located cylindrical rolls 127. The 15 inner race 126 is press-fitted upon a sleeve 128 which removably fits the reduced portion 115. There is a clearance between the annular plates 124 and the sleeve 128 while a nut 129 maintains the assembly of the anti-friction bearing 20 when it is slid off the reduced portion 115. A bearing cap 130 fitting in the recess 120 together with the annular flange 122 seals the bearing for retention of oil or grease and the exclusion of grit, while it is noted that the flange 122 is just 25 clear of the sleeve 128.

By reason of the construction described, the head 117 may be slid off the end of the spindle 36 at any time. The bearing just described is a radial bearing and takes no thrust, and preferably the heads 117 and 117a are not clamped upon the ways 116, 118 and 116a, 118a, thus permitting the parts to find their natural position without strain, and also allowing for expansion and contraction of the metal. However, I may provide suitable stops not shown, to prevent the heads 117 and 117a from moving out so far as to drop the spindles. 35

The sleeve 128 being on the reduced portion 115 with a press fit, by means of a lead hammer 40 either head may be moved outwardly to free the end of the spindle 36 or 36a as the case may be. The bearings including the rollers 37 and 43 are built to withstand the strain of the weight of spindles and wheels without any outer support, 45 as these bearings are double radial and thrust bearings spaced a substantial distance apart. Consequently it is a simple matter to place the wheels 101 to 108 or 101a to 108a upon the spindle 99 or 99a and secure them in place with the 50 washer 109 and nut 110 or washer 109a and nut 110a.

The wheels having been assembled, the machine may be used as described in the copending application referred to. As the machine is 55 used, the wheels will be dressed and trued from time to time to take care of wheel wear and adjustments. Each different position of skew of the wheels on the axes 14 and 23 respectively requires a new truing of the wheels in order to achieve 60 the best results in lapping. Consequently from the above causes and also by reason of normal wheel wear, the respective wheels 30 and 30a are continually becoming smaller in diameter. When the work-pieces are about to contact the washers 109 and 109a, I remove the wheels 30 and 30a (or only one of them if only one is considerably reduced in diameter) and the sections may be readily separated by knocking them with a lead hammer, as the cement is not and should not be 65 a permanent adhesive. However, I prefer merely to knock off the small section 108 or 108a, and then I slide a new unused section 101 or 101a upon the spindle 99 or 99a coating the small face thereof with a cement, and then slide the 70 75

old sections 101 to 107 inclusive, or 101a to 107a inclusive upon the spindle 99 or 99a. I then tighten up the nut 110 or 110a as before. The result is a fresh wheel, which may be trued to exact frusto-conical or other spiral form or shape, and the total discarded or unused wheel volume is indicated by the very close cross-hatching on section 108 on Figure 1. How this compares with what would be discarded were unit wheels used 10 can be appreciated by reference to Figure 1, drawing lines from the outside of flange 97 to the outside of washer 109. Furthermore, by means of the construction described, the renewal of 15 wheels may be made very quickly. Preferably wheels are renewed when all sections have been worn so that their large diameters are equal to the original size of their small diameters, as by 20 this procedure a minimum of dressing or truing is required. A circle may be painted on each 25 wheel, on the small side thereof, to represent this diameter for the small wheel 108 or 108a, since eventually every wheel moves to that position. It will be noted that all nuts have been shown as spanner nuts which facilitates the assembly and disassembly of the parts.

Although I have described the assembly of the wheels 30 and 30a upon the spindles 99 and 99a with the latter upon the spindles 36 and 36a, it 30 is quite convenient to remove the latter spindles from the former spindles for this purpose.

It will thus be seen that there has been provided by this invention an apparatus and a composite wheel in which the various objects hereinabove set forth together with many thoroughly practical advantages are successfully achieved. 5 As many possible embodiments may be made of the above invention, and as many changes might be made in the embodiment above set forth, it is to be understood that all matter hereinbefore set forth, or shown in the accompanying drawings, 10 is to be interpreted as illustrative and not in a limiting sense.

I claim:—

1. In apparatus of the class described, a pair of tables in parallel relationship, a pair of fixed heads one on each table, a pair of movable heads one on each table, spindles journaled in said heads, each spindle extending between a fixed head and a movable head and each movable head being movable in the direction of the spindle axis, 15 and the fixed head on one table being opposite the movable head on the other table, and frusto-conical abrasive wheels mounted on said spindles with the large end of one wheel opposite the small wheel of the other. 20

2. In apparatus as claimed in claim 1, the combination with the parts therein specified of a plurality of frusto-conical abrasive sections constituting the frusto-conical abrasive wheels. 25

HERBERT S. INDGE. 30
